ABSTRACT

A coin chute for a vending machine may include one or more anti-fishing assemblies located in the vicinity of the coin chute's opening for receiving coins. The anti-fishing assemblies may include one or more rotatable anti-fishing fingers that project into a coin channel. The anti-fishing fingers may rotate out of the coin channel to allow inserted coins to pass. In addition, the anti-fishing fingers prevent withdrawal of inserted coins out of the coin channel. The anti-fishing assemblies may be in addition to anti-pull back assemblies that prevent inserted coins from being withdrawn back past a coin discriminator.

**COIN CHUTE WITH ANTI-FISHING
ASSEMBLY**

TECHNICAL FIELD

The current application relates to coin chutes, and in particular to coin chutes that impede the fishing of coins.

BACKGROUND

Devices and machines that accept coins for payment, such as parking meters and vending machines, are typically unattended and located in public areas. As such, they are sometimes the subject of vandalism, and theft of, for example, either the parking meter itself or the coins used to pay for parking. With respect to parking meters, they generally include a coin chute into which coins are inserted. As the coin passes through the coin chute it may pass an arrangement of one or more sensors, typically inductive coils that can discriminate the value of the coin. When a coin passes through such a coin discriminator comprising discrimination sensors in the meter it travels from the upper portion of the parking meter housing and enters into a coin canister located in a lower vault, which is secured against theft by way of a hardened and locked housing.

Some coin chutes have an anti-pull back device (or assembly) that prevents or impedes coins from being pulled back and out of the coin chute. For example, pulling a coin back and out of the coin chute may be done by using a string fastened to the coin, and then pulling the coin out of the chute after the coin has fallen down the coin chute and been detected by the discrimination sensors. By employing an anti-pull back device, the same coin is prevented from being pulled back up the chute. This in turn prevents the same coin from passing through the discrimination sensors multiple times in order to receive credit for paid parking time without having deposited the required amount of coins. These anti-pull back devices can be found both in the meter, as well as at the entrance to the coin canister located in the lower vault area. The anti-pull back devices may be mechanical and may include a plurality of hinged fingers crossing the coin path. When the coin travels down the coin chute, the fingers may rotate out of the way. However, when the coin is attempted to be retrieved and pulled back up the coin chute, the fingers may be prevented from rotating out of the way.

While anti-pull back devices can prevent or impede pulling back the same coin in order to be counted numerous times, they may not prevent or impede all types of schemes to defraud a parking authority, or the public, of money. For example, a vandal or thief may force a foreign object into the coin chute in order to cause a jam in the coin chute, such as a jam just above the anti-pull back device that is located further down the coin chute. The foreign object may be non-metallic so that it may not be detected by sensors in the coin chute, which results in the parking meter remaining in service. When an unsuspecting customer attempts to make a payment, the inserted coins will remain in the coin chute instead of passing into the coin vault area. The thief or vandal may then attempt to fish out the inserted coins that are still in the coin chute.

An improved, additional or alternative coin chute that can impede the fishing of inserted coins from the coin chute is desirable.

SUMMARY

In accordance with the present disclosure, there is provided a coin chute for use in a vending machine comprising:

a coin channel defined by a first sidewall and a second sidewall opposite the first sidewall, the channel having a first portion through which coins may be inserted into the coin chute, and a second portion through which coins exit the channel; a coin discriminator for determining a denomination of coin passing the discriminator; and a first anti-fishing assembly located between the first portion of the channel and the coin discriminator comprising an anti-fishing finger rotatable between a first position in which the anti-fishing finger extends across the channel and a second position in which the anti-fishing finger is rotated out of the channel.

In an embodiment, the coin chute further comprises a second anti-fishing assembly located between the first portion of the channel and the coin discriminator comprising a rotatable anti-fishing finger.

In a further embodiment of the coin chute, the first anti-fishing assembly and the second anti-fishing assembly are offset horizontally from each other in the channel.

In a further embodiment of the coin chute, the first anti-fishing assembly and the second anti-fishing assembly are offset vertically from each other in the channel.

In a further embodiment of the coin chute, the first anti-fishing assembly and the second anti-fishing assembly are both located on a same one of the first or second sidewalls.

In a further embodiment of the coin chute, the first anti-fishing assembly and the second anti-fishing assembly are located on different ones of the first or second sidewalls.

In a further embodiment of the coin chute, the second anti-fishing assembly comprises a plurality anti-fishing fingers.

In a further embodiment of the coin chute, each of the plurality of anti-fishing fingers of the second anti-fishing assembly are independently rotatable.

In a further embodiment of the coin chute, the first anti-fishing assembly comprises a plurality of independently rotatable anti-fishing fingers spaced apart from each other by a first amount, and the second anti-fishing assembly comprises a plurality of independently rotatable anti-fishing fingers spaced apart from each other by a second amount different from the first amount.

In a further embodiment of the coin chute, each of the first anti-fishing assembly and the second anti-fishing assembly comprise an assembly frame securable to a coin chute frame, an axle secured between the assembly frame and the coin chute frame, wherein respective anti-fishing fingers are rotatably connected to the axle.

In a further embodiment of the coin chute, the first anti-fishing assembly and the second anti-fishing assembly are received within corresponding recesses within one of the first or second sidewalls.

In a further embodiment of the coin chute, first anti-fishing assembly is located adjacent and immediately below the first portion of the channel through which coins may be inserted.

In a further embodiment of the coin chute, the second anti-fishing assembly is located on an opposite side of the channel from the first portion of the channel through which coins may be inserted and at least partially above the first anti-fishing assembly.

In a further embodiment, the coin chute further comprises an anti-pull back assembly located between the second portion of the channel and the coin discriminator comprising an anti-pull back finger rotatable between a first position in which the anti-pull back finger extends across the channel

and a second position in which the anti-pull back finger is rotated out of the channel, wherein the anti-pull back finger is biased to the first position.

In a further embodiment of the coin chute, the anti-pull back assembly comprises a plurality of rotatable anti-pull back fingers.

In a further embodiment of the coin chute, at least one of the plurality of anti-pull back fingers is connected to the first sidewall and at least one of the plurality of anti-pull back fingers is connected to the second sidewall.

In a further embodiment of the coin chute, the first sidewall and second sidewall are connected to each other by one or more of: a snap-fit; an adhesive; and mechanical fasteners.

In a further embodiment of the coin chute, the coin channel comprises a third portion at an end of the channel opposite the second portion, and wherein said third portion comprises an opening for at least partially inspecting the coin channel.

In a further embodiment, the coin chute further comprises a housing at least partially surrounding at least the coin channel, coin discrimination and first anti-fishing assembly.

In a further embodiment of the coin chute, the housing comprises a cut-out to allow rotation of the anti-fishing finger of the first anti-fishing assembly.

In a further embodiment of the coin chute, the anti-fishing finger of the first anti-fishing assembly is coloured black or is a dark colour.

In a further embodiment of the coin chute, the plurality of anti-fishing fingers of the second anti-fishing assembly are coloured black or are a dark colour.

In a further embodiment of the coin chute, the plurality of anti-fishing fingers of the first anti-fishing assembly and the plurality of anti-fishing fingers of the second anti-fishing assembly are coloured black or are a dark colour.

In a further embodiment of the coin chute, the anti-fishing finger of the first anti-fishing assembly is not visible or is of reduced or limited visibility to a person at least horizontally peering into the coin chute at the first portion.

In a further embodiment of the coin chute, the plurality of anti-fishing fingers of the second anti-fishing assembly are not visible or are of reduced or limited visibility to a person at least horizontally peering into the coin chute at the first portion.

In a further embodiment of the coin chute, the plurality of anti-fishing fingers of the first anti-fishing assembly and the plurality of anti-fishing fingers of the second anti-fishing assembly are not visible or are of reduced or limited visibility to a person at least horizontally peering into the coin chute at the first portion.

In a further embodiment of the coin chute, the coin channel comprises an insert or filler that restricts or narrows the width of the coin channel.

In a further embodiment of the coin chute, the coin channel is restricted or narrowed such that the coin channel is only able to accommodate the width of one high value coin.

In a further embodiment of the coin chute, at least in part the insert or filler occupies a space extending from the first portion to the first anti-fishing device.

In accordance with the present disclosure, there is further provided a vending machine comprising: components for metering the sale of goods or services; and a coin chute as described herein.

In an embodiment of the vending machine, the goods or services metered comprises parking time for a parking space.

BRIEF DESCRIPTION OF THE DRAWINGS

Further features and advantages of the present disclosure will become apparent from the following detailed description, taken in combination with the appended drawings, in which:

FIG. 1 depicts a parking meter having a coin chute with an anti-fishing assembly;

FIG. 2 depicts a partially disassembled view of the parking meter 100 of FIG. 1;

FIG. 3 depicts a coin chute with an anti-fishing assembly used in the parking meter of FIGS. 1 and 2;

FIG. 4 depicts an interior of a side of the coin chute of FIG. 3;

FIG. 5 depicts a partially exploded view of the coin chute of FIG. 3;

FIG. 6 depicts an exploded view of the coin channel of the coin chute of FIGS. 3 and 5;

FIG. 7 depicts a side view of the wall of the coin channel wall of the coin chute of FIGS. 3, 5 and 6; and

FIG. 8 depicts an alternative anti-fishing finger.

DETAILED DESCRIPTION

25 A parking meter that incorporates a coin chute including an anti-fishing assembly or anti-fishing device may impede withdrawal of coins from a coin chute. As described further herein, the anti-fishing assembly (or device, as referred to interchangeably herein) may be incorporated into a coin chute during manufacture. The anti-fishing assembly may be incorporated into the coin chute in addition to an anti-pull back assembly that prevents or impedes a coin from being pulled back past a coin discriminator a plurality of times. As described further below, the anti-fishing assembly provides 30 an obstacle in a coin channel that impedes fishing coins from the coin channel as well as reduces the number of coins that can be held within the coin channel. As described further below, the anti-fishing assembly comprises at least one anti-fishing finger that is located within an upper section of 35 the coin channel.

FIG. 1 depicts a parking meter which incorporates a coin chute with an anti-fishing assembly in accordance with the present disclosure. The parking meter 100 is a single space parking meter. Although parking meter 100 is referred to as a single space parking meter, it may actually meter parking time for two or more parking spaces. Single space parking meters may comprise a removable parking meter mechanism 102 which is housed within a housing for the upper portion of the parking meter. As depicted in FIG. 1, the housing may 40 comprise a back housing 104 and a lower housing 106. The lower housing 106 may be attached to a coin vault 108 that may be typically installed on a pole near a parking location associated with the meter 100. The coin vault 108 may 45 include a coin canister and a vault door 110 that can be locked to prevent unauthorized access to coins being stored in the vault 108. The coins may be inserted into the parking meter mechanism 102. The coin enters a coin channel of a coin chute where a coin discriminator comprising sensor 50 circuitry can determine the denomination of the inserted coin. In order to prevent or impede withdrawal of inserted coins, anti-fishing assemblies as well as anti-pull back assemblies 55 may be incorporated into the coin chute.

60 The anti-fishing assemblies and anti-pull back assemblies are similar in purpose, namely to prevent or impede the withdrawal of inserted coins; however, each of the assemblies are directed to defeating different types of attacks. The

anti-pull back assemblies prevent or impede inserted coins from being pulled back past the coin discrimination circuitry to have a single inserted coin counted multiple times. The anti-fishing assemblies of the present invention prevent inserted coins from being withdrawn from the coin channel, even if they have not passed the coin discrimination circuitry. Additionally, the anti-fishing assemblies of the present invention reduce or at least somewhat minimize the volume in the coin channel within which coins can rest in the event of a blockage within the coin channel, and as such reduce the number of coins that could potentially be fished out. As an example, a coin chute having only anti-fishing assemblies may be susceptible to time theft by inserting a coin on a string and repeatedly pulling the coin back past the discrimination circuitry. Although the anti-fishing assemblies may prevent the inserted coin from being retrieved, the coin may be counted multiple times and as such a single coin such as a nickel or dime may be used to pay for a dollar, two dollars or more of parking time. While the anti-pull back assemblies may prevent such types of attack, if there is a blockage in the chute, coins may accumulate in the coin channel by resting on top of the blockage. These accumulated coins may then be fished out of the coin channel; the anti-pull back assemblies do not provide any deterrent to such an attack.

In addition, the removable parking meter mechanism 102 may comprise alternative payment means such as a card payment means 114. The parking meter mechanism 102 may include a solar panel 116 for charging a battery pack of the mechanism. The parking meter mechanism 102 may also include one or more input controls 118 for controlling operation of the meter mechanism, as well as a display 120 for displaying an amount of parking time purchased.

FIG. 2 depicts a disassembled view of the parking meter 100 of FIG. 1. As depicted, the removable parking meter mechanism 102 can be removed from the back housing 104 and the lower housing 106. The coin vault is not depicted in FIG. 2; however, it would be attached to the bottom of the lower housing 106. The removable parking meter mechanism 102 includes components for metering a parking spot, or spots. The metering components may include a display and control components as well as electronics for controlling the operation of the parking meter. The removable parking meter mechanism may include a battery pack 122 for powering the components of the removable parking meter mechanism 102. The removable parking meter mechanism 102 further comprises a coin chute 202 that includes a coin channel that allows a coin inserted into the coin slot of the parking meter to pass through a sensor, or sensors, that can discriminate the denomination of the inserted coin. A coin 204 that is inserted into the coin slot of the parking meter enters the coin channel and passes through the coin chute 202, as depicted by arrow 206. When the parking meter is assembled, as shown in FIG. 1, the coin 204 passes through the coin channel in the direction of arrow 206 and into the coin vault, as depicted by dashed line 208. The inserted coin passes through the coin chute by an anti-fishing assembly, a coin discriminator comprising circuitry and/or sensor(s), and possibly an anti-pull back assembly.

Although not depicted, multi-space parking meters often have a number of the same components as the single space parking meter 100 of FIGS. 1 and 2, including a housing, a display, a coin chute, a vault, a card payment means, a solar panel, and battery pack components. Multi-space parking meters differ from single space parking meters in that the multi-space meters are typically larger devices capable of managing parking payment and control for typically signifi-

cantly more than one or two parking spaces and possibly as many as hundreds of parking spaces. Notwithstanding any differences, multi-space parking meters may incorporate a coin chute with an anti-fishing assembly in accordance with the present disclosure. Further, the coin chute described herein may be used in not only parking meters, but also vending machines more generally, including for example single and multi-space parking meters, food and/or beverage vending machines, toy vending machines, electronics vending machines, as well as other vending machines that accept payment for a good or service in coins or tokens.

A thief wishing to defraud a parking authority may do so in a number of different types of attacks. For example, a thief may place a coin attached to a string into the coin chute. Once the coin passes the coin discriminator, the thief can pull the coin up past or above the coin discriminator, and then allow the coin to be lowered and pass through the discriminator again. In order to prevent this type of theft, the coin chute 202 may include an anti-pull back assembly that prevents a coin 204 from being pulled up the coin chute once it has passed the coin discriminator. In addition, if the coin travels into the coin canister in the vault area, the coin canister may also have built-in anti-pull back levers that will trap the coin inside the coin canister. The anti-pull back assembly may comprise a number of moveable fingers that are pivoted out of the path of a downward-moving coin by the downward force of the coin, but are prevented from pivoting out of the coin path when the coin is pulled upwards. Although the anti-pull back device can prevent a single coin from being counted a plurality of times, other types of fraud are possible. For example, a thief or vandal may insert an object into the coin channel to block the channel. In this situation, when a user inserts a coin, it will enter the coin channel; however, it will not pass the anti-pull back assembly due to the foreign object jam. The inserted coin or coins will remain in the coin channel, and once the user leaves the parking meter, the thief may approach the meter and fish the inserted coins out of the coin channel. The addition of optical sensors incorporated into the coin chute, along with corresponding software, could provide additional detection of jams within the coin channel and place the parking meter into a non-functioning state; however, retrofitting or adding the required optical sensors to the coin chute may not be possible or practical, and may require replacement of the entire coin chute assembly. Moreover, additional sensors and/or software may result in increased power consumption, which is generally undesirable for unattended vending machines, including parking meters, which typically rely upon batteries for power supply.

In order to discourage fishing types of theft, an anti-fishing assembly may be incorporated into the coin chute. The anti-fishing assembly is preferably placed as close as possible to the insertion point of the coin chute but without being visible, or being of reduced or limited visibility, to a person at least horizontally peering into the coin chute at coin slot 112. Placing the anti-fishing assembly as close as possible to the insertion point of the coin chute in this regard reduces or at least somewhat minimizes the volume in the coin channel within which coins can rest in the event of a blockage within the coin channel, and as such reduce the number of coins that could potentially be fished out. As described further herein, the anti-fishing assembly may comprise one or more fingers that extend from a side of the coin channel into the coin channel. The fingers allow a coin to be inserted into the coin channel; however, if the coin is attempted to be withdrawn from the coin channel, the fingers may block the coin from being withdrawn.

A coin chute with an anti-fishing assembly used in the parking meter of FIGS. 1 and 2, or more broadly in vending machines in general, is described with particular reference to FIGS. 3-7. As best depicted in FIG. 3, the coin chute 202 may be provided as a modular component that can be incorporated into, for example, parking meters. The coin chute 202 may have an exterior housing, which may be formed from two connected halves 302a, 302b. The coin chute includes an opening or entrance 304 through which coins can be inserted. The coins enter the coin chute and fall through the coin chute and exit through a bottom 306 of the coin chute. In addition to the coin entrance 304, the coin chute may also include an inspection or maintenance opening 308 that allows the interior coin channel 318 of the coin chute to be visually inspected, as well as facilitation of maintenance such as removing or clearing blockages.

When a coin is inserted into the coin chute, it passes through the opening 304 and into a coin channel. The coin channel 318 may be formed from two connected walls 318a, 318b (see FIG. 6). The coin falls down the coin channel and passes a coin discriminator comprising one or more discrimination components that can determine a denomination of the coin. The coin chute 202 has a discriminator that comprises two main sections. Although the actual discrimination components are not depicted in the Figures, the locations of the components are shown. The first component of the discriminator is a horizontal coil wound about the coin channel. The coil may be wound about the coin channel to form a loop or rounded section 310 such that coins passing through the coin channel pass through the center of the coil loop. A second component of the discriminator comprises a pair of horizontally aligned coils. The coils may be located on, or supported by, respective ends 312a, 312b (see FIG. 5) of the coin channel. Regardless of the coin discriminator used, the coin chute 202 may include a number of anti-pull back devices 328a, 328b, 328c (referred to collectively as anti-pull back device 328) that prevent a coin from being pulled up or withdrawn past the coin discriminator, or at least a portion of the coin discriminator such as the horizontal coil loop located at the rounded section 310. The coin chute 202 may include further electronic components. Although not depicted, the components may include, for example, a coin proximity detector comprising a pair of coil loops located at either side 326 of the entrance 304 of the coin chute.

The coin chute 202 includes an anti-fishing device, or anti-fishing devices, 314, 316. Like the anti-pull back devices 328, the anti-fishing devices 314, 316 prevent, or at least hinder, the withdrawal of coins from the coin chute. In particular, the anti-fishing devices 314, 316 prevent or hinder the withdrawal of coins that may be resting in the coin chute above the anti-pull back device 328. The anti-fishing devices 314, 316 are located within the coin channel 318 so that they impede withdrawal of coins. As depicted in FIG. 3, there are two anti-fishing devices with one device 316 located at least slightly below a lower edge of the coin chute entrance 304 and towards the side of the coin chute where the coin entrance 304 is located. The other one of the anti-fishing devices 314 is located on the side of the coin chute away from the coin chute entrance 304 and may be located at a slightly higher location within the coin chute than the other anti-fishing device 316.

The anti-fishing devices 314, 316 may include a plurality of spaced apart rotatable fingers. The fingers may be constructed or assembled in a manner similar to or the same as the manner in which fingers for known anti-pull back devices are constructed or assembled. For example, the

fingers of anti-fishing devices 314, 316 may rotate into the coin channel under the force of gravity, or some other slight biasing means. In order to allow the fingers to rotate freely within the coin channel, the outer housing 302a of the coin chute may include a cut out portion 330 to allow the fingers to rotate. When a coin is inserted into the coin channel, the coin passes down the coin channel and the force of the coin rotates the fingers out of the coin channel. Once the coin passes the anti-fishing devices, the fingers rotate back into the coin channel to prevent any coins that may be at rest in the coin channel from being pulled up or withdrawn past the anti-fishing devices and out of the coin channel. The anti-fishing devices 314, 316 reduce the volume of space within the coin channel in which coins may be at rest. For example, the anti-fishing devices 314, 316 reduce the available volume of space within the coin channel that may be available for accumulating and withdrawing coins due to a jam, or obstruction in the coin channel. This is because coins accumulated below or downstream of the anti-fishing devices due to jams or obstructions located below or downstream of the anti-fishing devices 314, 316 are not available for withdrawal as a result of the operation of the anti-fishing devices 314, 316. Preferably, and as shown in FIG. 5, the locating of the anti-fishing device 316 at or just below the bottom of coin chute entrance 304, and the anti-fishing device 314 across and above from the anti-fishing device 316, provides anti-fishing coverage across the width of the coin channel 318. Further, such an arrangement reduces or at least somewhat minimizes the volume in the coin channel within which coins can rest in the event of a blockage within the coin channel. As such, the number of coins that could potentially be fished out is reduced. Moreover, because such an arrangement includes anti-fishing device components at least somewhat below the bottom of the coin chute entrance 304, defeating or circumventing the anti-fishing devices 314, 316 is more difficult than in an implementation where the devices are located in a higher and/or more visible or accessible location in the coin chute.

As depicted in FIG. 6, the anti-fishing devices 314, 316 may comprise a frame 332, 336 that each allow anti-fishing fingers to be rotatably mounted at the coin channel. The frames 332, 336 allow anti-fishing fingers 320a, 320b, 322a, 322b to be mounted to the coin channel wall 318a. As depicted, the coin channel wall 318a may include one or more locations, depicted as recesses 338, 340, for mounting the anti-fishing devices 314, 316. The spacing between the fingers 320a, 320b and 322a, 322b may vary between the different anti-fishing devices 314, 316. For example, the spacing between fingers 320a, 320b of anti-fishing device 314 may be less than the spacing between fingers 322a, 322b of anti-fishing device 316. The recess 338 may include an opening 344 through which the fingers may protrude into the coin channel. The recess may also include a further indentation or recess 342 for securely fitting the rod or axle used for rotatably connecting the fingers 320a, 320b to the coin channel wall 318a. The frame 332 may be secured to the wall 318a thereby securing the rod and fingers in place. The second frame 336 may similarly secure the fingers 322a, 322b to the coin channel wall 318a by securing the frame 336 within the recess 340. As noted above, the frame 336 may provide a wider spacing between the fingers 322a, 322b as compared to the spacing between fingers 320a, 320b. Similarly, the recess 340 may include two separate openings 346a, 346b through which the fingers 322a, 322b may respectively protrude into the coin channel. Varying the spacing of the fingers in this regard facilitates providing anti-fishing coverage across the width of the coin channel,

and reducing or at least somewhat minimizing the volume in the coin channel within which coins can rest in the event of a blockage within the coin channel.

As discussed above and depicted in the Figures, the anti-fishing device 316, which is located on the side of the coin channel that is towards the coin entrance (as opposed to away from the coin entrance as is the case with anti-fishing device 314), may have a wider spacing between its fingers in order to impede fishing of larger sized coins. The anti-fishing device 314 may have narrower spacing between its fingers and may be located further up the coin channel relative to anti-fishing device 316. The narrower spacing of the fingers may be useful in preventing the withdrawal of smaller sized coins.

FIG. 8 depicts an alternative anti-fishing finger. As described above, anti-fishing fingers may be rotatably connected to the coin chute on a rod or axle. The fingers comprise a hole through which the rod or axle may be inserted. Alternatively, as depicted in FIG. 8, the anti-fishing fingers 800 may be formed as a single component that includes a protruding finger portion 802 that includes an end 804 that protrudes into the coin channel. The anti-fishing finger 800 may include rod-like protrusions that form pivot point 806 and allow the finger 800 to rotate when loosely secured to the coin channel wall. While the above embodiment depicted the anti-fishing fingers as being secured to the coin channel through a frame, it is possible that the anti-fishing fingers, including anti-fishing fingers such as finger 800, may be secured in other manners. For example, the anti-fishing assembly may comprise the anti-fishing finger 800 and a protrusion or other similar structure formed with, or attached to, the channel wall. The protrusion, or other similar structure, may engage the anti-fishing finger in order to rotatably secure the finger to the channel wall.

The anti-fishing finger 800, as well as the anti-fishing fingers described above, may include a counter weight portion 808 on the opposite side of the pivot point 806. The counter weight portion 808 may provide sufficient weight to rotate downward and cause the end of the finger 804 to rotate into the coin channel. The counter weight portion 808 is light enough so that the anti-fishing finger may be rotated out of the coin channel under the weight of a falling coin.

Preferably, the fingers of the present description are coloured black or a dark colour so that a person peering into a coin channel would have greater difficulty identifying or locating any fingers than if the fingers were of a bright or light colour. Minimizing the visibility of the fingers to potential vandals and thieves is preferred.

In order to further minimize the amount of theft of coins by vandals or thieves that may engage in fishing activities with respect to coin chutes, an insert or filler piece/object (not shown in the Figures) may be inserted into the coin channel such that the insert or filler object occupies a space extending from the entrance to the coin channel to the anti-fishing devices, either in whole or in part. The purpose of the insert or filler object is to restrict or narrow the width of the coin channel. By narrowing the width of the coin channel to, for example, accommodate the width of only one high value coin, the ability to fish coins is impeded, as the insert or filler prevents multiple coins from accumulating side-by-side in the coin channel.

A coin chute incorporating an anti-fishing device, as well as a parking meter incorporating a coin chute with an anti-fishing device, have been described by way of examples. It will be appreciated that components of one example may be incorporated into another example. Furthermore, although specific embodiments of a coin chute are

described, it will be appreciated that anti-fishing fingers may be incorporated into coin chutes of different designs. Variations and modifications not described herein will be apparent to one of ordinary skill in the art having regard to the description herein.

What is claimed is:

1. A coin chute for use in a vending machine comprising: a coin channel defined by a first sidewall and a second sidewall opposite the first sidewall, the channel having a first portion through which coins may be inserted into the coin chute, and a second portion through which coins exit the channel;

a coin discriminator for determining a denomination of coin passing the discriminator; and a first anti-fishing assembly located between the first portion of the channel and the coin discriminator comprising an anti-fishing finger rotatable between a first position in which the anti-fishing finger extends across the channel to prevent coins that have not passed the coin discriminator from being retracted from the coin channel and a second position in which the anti-fishing finger is rotated out of the channel to allow coins to pass the coin discriminator.

2. The coin chute of claim 1, wherein the first sidewall and second sidewall are connected to each other by one or more of:

a snap-fit;
an adhesive; and
mechanical fasteners.

3. The coin chute of claim 1, wherein the coin channel comprises a third portion at an end of the channel opposite the second portion, and wherein said third portion comprises an opening for at least partially inspecting the coin channel.

4. The coin chute of claim 1, wherein the anti-fishing finger of the first anti-fishing assembly is coloured black or is a dark colour.

5. The coin chute of claim 1, wherein the anti-fishing finger of the first anti-fishing assembly is not visible or is of reduced or limited visibility to a person at least horizontally peering into the coin chute at the first portion.

6. The coin chute of claim 1, further comprising a housing at least partially surrounding at least the coin channel, coin discriminator and first anti-fishing assembly.

7. The coin chute of claim 6, wherein the housing comprises a cut-out to allow rotation of the anti-fishing finger of the first anti-fishing assembly.

8. A vending machine comprising:
components for metering the sale of goods or services;
and
a coin chute according to claim 1 for receiving coins for purchasing the goods or services.

9. The vending machine of claim 8, wherein the goods or services metered comprises parking time for a parking space.

10. The coin chute of claim 1, further comprising:
an anti-pull back assembly located between the second portion of the channel and the coin discriminator comprising an anti-pull back finger rotatable between a first position in which the anti-pull back finger extends across the channel and a second position in which the anti-pull back finger is rotated out of the channel, wherein the anti-pull back finger is biased to the first position.

11. The coin chute of claim 10, wherein the anti-pull back assembly comprises a plurality of rotatable anti-pull back fingers.

11

12. The coin chute of claim **11**, wherein at least one of the plurality of anti-pull back fingers is connected to the first sidewall and at least one of the plurality of anti-pull back fingers is connected to the second sidewall.

13. The coin chute of claim **1**, wherein the coin channel comprises an insert or filler that restricts or narrows the width of the coin channel.

14. The coin chute of claim **13**, wherein the coin channel is restricted or narrowed such that the coin channel is only able to accommodate the width of one high value coin.

15. The coin chute of claim **13**, wherein at least in part the insert or filler occupies a space extending from the first portion to the first anti-fishing device.

16. The coin chute of claim **1**, further comprising a second anti-fishing assembly located between the first portion of the channel and the coin discriminator comprising a rotatable anti-fishing finger.

17. The coin chute of claim **16**, wherein the first anti-fishing assembly and the second anti-fishing assembly are offset vertically from each other in the channel.

18. The coin chute of claim **16**, wherein the first anti-fishing assembly and the second anti-fishing assembly are both located on a same one of the first or second sidewalls.

19. The coin chute of claim **16**, wherein the first anti-fishing assembly and the second anti-fishing assembly are located on different ones of the first or second sidewalls.

20. The coin chute of claim **16**, wherein first anti-fishing assembly is located adjacent and immediately below the first portion of the channel through which coins may be inserted.

21. The coin chute of claim **20**, wherein the second anti-fishing assembly is located on an opposite side of the channel from the first portion of the channel through which coins may be inserted and at least partially above the first anti-fishing assembly.

22. The coin chute of claim **16**, wherein the first anti-fishing assembly and the second anti-fishing assembly are offset horizontally from each other in the channel.

23. The coin chute of claim **22**, wherein the first anti-fishing assembly and the second anti-fishing assembly are offset vertically from each other in the channel.

24. The coin chute of claim **23**, wherein the first anti-fishing assembly comprises a plurality of independently rotatable anti-fishing fingers spaced apart from each other by a first amount, and the second anti-fishing assembly comprises a plurality of independently rotatable anti-fishing fingers spaced apart from each other by a second amount different from the first amount.

25. The coin chute of claim **23**, wherein first anti-fishing assembly is located adjacent and immediately below the first

12

portion of the channel through which coins may be inserted, and the second anti-fishing assembly is located on an opposite side of the channel from the first portion of the channel through which coins may be inserted and at least partially above the first anti-fishing assembly.

26. The coin chute of claim **16**, wherein the second anti-fishing assembly comprises a plurality anti-fishing fingers.

27. The coin chute of claim **26**, wherein each of the plurality of anti-fishing fingers of the second anti-fishing assembly are independently rotatable.

28. The coin chute of claim **26**, wherein the plurality of anti-fishing fingers of the second anti-fishing assembly are coloured black or are a dark colour.

29. The coin chute of claim **26**, wherein the plurality of anti-fishing fingers of the second anti-fishing assembly are not visible or are of reduced or limited visibility to a person at least horizontally peering into the coin chute at the first portion.

30. The coin chute of claim **16**, wherein the first anti-fishing assembly comprises a plurality of independently rotatable anti-fishing fingers spaced apart from each other by a first amount, and the second anti-fishing assembly comprises a plurality of independently rotatable anti-fishing fingers spaced apart from each other by a second amount different from the first amount.

31. The coin chute of claim **30**, wherein each of the first anti-fishing assembly and the second anti-fishing assembly comprise an assembly frame securable to a coin chute frame, an axle secured between the assembly frame and the coin chute frame, wherein respective anti-fishing fingers are rotatably connected to the axle.

32. The coin chute of claim **31**, wherein the first anti-fishing assembly and the second anti-fishing assembly are received within corresponding recesses within one of the first or second sidewalls.

33. The coin chute of claim **30**, wherein the plurality of anti-fishing fingers of the first anti-fishing assembly and the plurality of anti-fishing fingers of the second anti-fishing assembly are coloured black or are a dark colour.

34. The coin chute of claim **30**, wherein the plurality of anti-fishing fingers of the first anti-fishing assembly and the plurality of anti-fishing fingers of the second anti-fishing assembly are not visible or are of reduced or limited visibility to a person at least horizontally peering into the coin chute at the first portion.
